E. W. BOWEN

SWIMMING POOL

Filed July 3, 1924

Fig. 2.

Fig. 3.

Inventor:
Edgar Wright Bowen,

E. Wright Bowen
Atty.

UNITED STATES PATENT OFFICE.

EDGAR W. BOWEN, OF JACKSONVILLE, FLORIDA.

SWIMMING POOL.

Application filed July 3, 1924. Serial No. 724,157.

To all whom it may concern:

Be it known that I, EDGAR W. BOWEN, a citizen of the United States, residing at Jacksonville, in the county of Duval and State of Florida, have invented certain new and useful Improvements in Swimming Pools, of which the following is a specification.

My said invention relates to a swimming pool intended primarily for instruction of novices and especially children in the art of swimming. It is an object of the invention to provide a device of this character which shall be safe, simple and of inexpensive construction.

Another object of the invention is to provide a device of the character in which a current of water shall be created in a direction to assist and encourage the learner.

Another object of the invention is to provide a separate body of water in a basin or container forming part of the same structure, which body shall be of ordinary temperature and of sufficient depth for use by those competent in the art of swimming.

Referring to the accompanying drawings, which are made a part hereof and on which similar reference characters indicate similar parts,

Figure 1 is a plan of the device of my invention,

Figure 2, a section on line 2—2 of Figure 1, and

Figure 3, a section on line 3—3 of Figure 1.

In the drawings reference character 10 indicates the bottom of a tank which may be formed in one piece with sides 11 and ends 12, the bottom preferably, though not necessarily, being stepped as shown in Figure 3 to correspond to the different depths of different parts of the construction which I have called a tank. Partition walls 13, 14 and 15 may also be formed integral with the bottom and side walls of the tank. As a matter of convenience I have shown the parts above referred to as being made of concrete. It will be understood that any desirable or conventional material may be used.

The partition walls divide the interior of the tank to form a tortuous channel having parallel portions or compartments of which the compartment at 16 is separate and dis-

tinct from the others and is of such a size and depth as may be considered desirable for the use of swimmers not needing primary instruction. This compartment has flights of steps at 17 and 18 leading down into it and hand rails at 20 alongside the steps. An inlet is shown at 21, an outlet at 22 and an overflow pipe at 23 for regulating the normal level of the water.

The remaining compartments are connected to permit the water to flow from one to the other compartment the one at 24 being the shallowest and the one in which children will first start to learn. The construction is not necessarily limited to children as the dimensions of the device may be such as to provide for instruction of adults, or separate devices may be provided for persons of different ages. Steps at 25 lead down to the compartment 24, hand rails 25' being provided along said steps, and a rise at 26 approximately midway of the length of the compartment is arranged to provide a resting place and also a place over which the pupil must climb, the purpose being to impress on him that the water will support him and that the compartment is shallow.

This rise has sloping sides to prevent persons from bumping abruptly against it and hurting themselves, and is under water. Preferably it is covered with soft material, such as canvas. At the end of this first compartment there is a step 27 by means of which persons may leave at this point and return to the steps 25 to pass through this section as often as they may desire or deem necessary. At the end adjacent the step 27 the first compartment communicates with another section 28 through a barrier 29 perforated to permit the water to pass as indicated in Figure 3. The purpose of this arrangement is to permit water to flow freely from compartment 24 to compartment 28 but to make it necessary for pupils to rise and step over the perforated barrier 29.

The compartment 28 is similar to compartment 24, the rise 26 extending crosswise through all the instruction compartments or at least through the first two and is separated at its further end from the compartment 30 by another barrier 29. A step 31 provides means for egress at the end of compartment 28, if desired, this compartment being deeper than compartment 24 as will be

evident from consideration of Figure 3. The compartment 30 is similar to those previously described except that it is deeper and may not have a rise 26. At the left-hand end of the compartment there is a flight of steps 32 by which persons may leave the tortuous instruction course and return to the beginning at 25 or re-enter it at some other place, or if desired may pass to the compartment 16.

Water for use in the tortuous channel enters under the steps at 32. This may come from any natural or artificial source. A pump 33 driven by a motor 34 propels the water into and through a passage indicated in dotted lines at 35, said passage extending from the partition 13 and opening under the steps 25. The pump may be dispensed with where water under pressure is available. A continuous circulation of water is preferably kept up, the current passing to the left through the compartment 24 of the tortuous passageway, then to the right through compartment 28, then to the left through compartment 30, at the left-hand end of which it may pass out through a pipe 36 which pipe also serves to determine the level of the water in such tortuous course.

30 A number of drains are indicated at 37 it being necessary to provide drains for each of the compartments defined by the barrier 26 and the adjacent walls. It is desirable that the means for distribution of water such as inlet and outlet passages should be controlled from a single position on the tank, e. g. at some point near the motor 34 and ways of doing this will be obvious to those skilled in the art of plumbing.

40 At certain seasons of the year it will be desirable to warm the water in the tank, especially for instruction of children and for this purpose I have shown a heating device at 38 having pipes 39 for steam or hot water leading therefrom into the space underneath the steps 32. The showing of this device is merely conventional as the heating means may be of any desired form and may be connected in any desirable way to the source of fluid supply, preferably so as to heat the incoming water.

It will be obvious to those skilled in the art that this and other details of the device 55 may be changed in many ways without departing from the spirit of the invention and therefore I do not limit myself to the specific embodiment of the invention shown in the drawings and described in the specification but only as indicated in the appended claims.

Having thus fully described my said invention, what I claim as new and desire to secure by Letters Patent is:

35 1. Means for instruction in swimming

comprising a tortuous channel having parallel portions of different depths, and perforated barriers separating said portions of different depths from one another, substantially as set forth.

2. A swimming pool comprising a tank having a tortuous passage for inexperienced swimmers, and a plurality of barriers extending from the bottom of said passage, substantially as set forth.

3. A swimming pool comprising a tank having a plurality of communicating channels of different depths, and barriers located in said channels, substantially as set forth.

4. In combination in a swimming pool a receptacle having a plurality of reservoirs provided with stepped bottom surfaces forming pools of different depths, one of said pools being separate and distinct and the other of said pools being joined to provide a continuous water passage but having means for preventing the passage of swimmers, substantially as set forth.

5. In combination in a swimming pool a receptacle having a plurality of reservoirs provided with stepped bottom surfaces forming pools of different depths, the pool of greatest depths being separate and distinct and the other of said pools having their ends joined to provide a tortuous water passage, and obstructions located in said pools requiring swimmers to emerge from the water to pass thereover, substantially as set forth.

6. A swimming pool comprising a tank having a tortuous passage for inexperienced swimmers, and a plurality of barriers extending from the bottom of said passage, and a separate and distinct compartment for experienced swimmers, substantially as set forth.

7. In combination in a swimming pool, a tank having a compartment for experienced swimmers provided with steps at each end, a plurality of compartments having their bottom surfaces stepped to provide pools of different depths said pools being joined at their contiguous ends and forming a tortuous passage, said adjoining ends being provided with barriers permitting water to pass therethrough but requiring swimmers to pass over the same, obstructions located intermediate the ends of one of said compartments beneath the normal surface of the water, substantially as set forth.

8. In combination in a swimming pool, a tank having a compartment for experienced swimmers provided with steps at each end, a plurality of compartments having their bottom surfaces stepped to provide pools of different depths said pools being joined at their contiguous ends and forming a tortuous passage, said adjoining ends being provided with barriers permitting water to pass therethrough but requiring

swimmers to pass over the same, obstructions located intermediate the ends of one of said compartments beneath the normal surface of the water, and means for producing a current in said water, substantially as set forth.

In witness whereof, I have hereunto set

my hand and seal at Washington, District of Columbia, this second day of July, A. D. nineteen hundred and twenty-four.

EDGAR W. BOWEN.
